UNITED STATES PATENT OFFICE

172,980

VENDING MACHINE

Anton Obodzinski, Chicago, Ill.

Application August 18, 1953, Serial No. 26,501

Term of patent 3½ years

(Cl. D52—3)

To all whom it may concern:

Be it known that I, Anton Obodzinski, a citizen of the United States and resident of Chicago, in the county of Cook and State of Illinois, have invented a new, original, and ornamental Design for a Vending Machine, of which the following is a specification, reference being had to the accompanying drawing, forming a part thereof.

Fig. 1 is a perspective view of a vending machine, showing my new design;

Fig. 2 is a side elevational view of the same vending machine; and

Fig. 3 is a top plan view of the same.

The rear of the machine and the side not shown are substantially plain.

I claim:

The ornamental design for a vending machine, substantially as shown and described.
